(57) **CLAIM**

The ornamental design for a stripped screw extractor, as shown and described.

DESCRIPTION

FIG. 1 is a perspective view of a stripped screw extractor in accordance with the new design;

FIG. 2 is a front view of the grip enhancing formation of a tool body stripped screw extractor of FIG. 1;

FIG. 3 is a rear view of the stripped screw extractor of FIG. 1;

FIG. 4 is a left side view of the stripped screw extractor of FIG. 1;

FIG. 5 is a right side view of the stripped screw extractor of FIG. 1;

FIG. 6 is a top view of the stripped screw extractor of FIG. 1; and,

FIG. 7 is a bottom view of the stripped screw extractor of FIG. 1.

In the drawings, the even length broken lines and the dot-dash boundary lines illustrate portions of the stripped screw extractor that form no part of the claimed design.

1 Claim, 7 Drawing Sheets
